(57) **CLAIM**

The ornamental design for a tool trigger, as shown and described.

DESCRIPTION

FIG. 1 is a right side elevation view of the tool trigger in an assembled state with an environmental drill structure;

FIG. 2 is a perspective view of the tool trigger;

FIG. 3 is a right elevation view thereof;

FIG. 4 is a left elevation view thereof;

FIG. 5 is a front elevation view thereof;

FIG. 6 is a bottom plan view thereof; and,

FIG. 7 is a top plan view thereof.

The broken line showing of the drill is for the purpose of illustrating environmental structure and forms no part of the claimed design.
